UNITED STATES PATENT OFFICE.

HENRY G. CORDLEY, OF GLEN RIDGE, NEW JERSEY, AND GEORGE R. LONG, OF WATERBURY, CONNECTICUT, ASSIGNEES TO CORDLEY & HAYES, OF NEW YORK, N. Y., A CORPORATION OF NEW YORK.

LIQUID-DISPENSING DEVICE.

1,326,253.

Specification of Letters Patent. Patented Dec. 30, 1919.

Application filed May 8, 1919. Serial No. 295,663.

To all whom it may concern:

Be it known that we, HENRY G. CORDLEY, a citizen of the United States, residing at Glen Ridge, in the county of Essex, State of New Jersey, and GEORGE R. LONG, a citizen of the United States, residing at Waterbury, in the county of New Haven, State of Connecticut, have invented certain new and useful Improvements in Liquid - Dispensing Devices, of which the following is a description, reference being had to the accompanying drawings, forming a part hereof.

Our invention relates to liquid dispensing devices and has for its object to provide a liquid dispensing device adapted to dispense liquids, such as grape juice and the like, from the original bottle or container, in measured quantity, which will be simple in construction, certain in operation, easily taken apart for cleaning or shipment and neat and attractive in appearance.

With these and other objects hereinafter explained in view, our invention consists in the construction and combination of elements hereinafter described and particularly pointed out in the claims.

Referring to the drawings. Figure 1 is a vertical central sectional view of a complete dispensing device embodying our invention; Fig. 2 is a front elevation of the dispensing device; Fig. 3 is a top plan view of the supporting means; Fig. 4 is a vertical sectional view of a modified form of piston and Fig. 5 is a vertical sectional view of a modified form of top for the measuring chamber.

In the drawings 1 indicates a container open at its upper end adapted to receive the inverted bottle 2. 3 indicates a measuring chamber arranged in front of the container 2 and preferably formed in one piece with it. The container 1 and measuring chamber are preferably arranged on a common base 4, having an annular recess 5 in its lower face near its periphery, to receive a ring 6 carrying depending legs 7 to form the supporting means for the device.

In its central part the lower face of the base 4 is flat as shown at 8 with openings 9 and 10 through it communicating respectively with the container 1 and the measuring chamber 3, and the base is provided on its lower face between the flat face 8 and the annular recess 5 with outwardly projecting slotted lugs 12.

To the lower face of the base is secured a valve carrier 13. This valve carrier has a disk 14 with its upper face flat to fit against the flat face 8 of the base and this disk is provided in its periphery with bolts 15 adapted to fit the slots of the lugs 12, having heads 16 on their upper ends adapted to engage the upper faces of the lugs and thumb nuts 17 on their lower ends bearing against the lower face of the disk. Below the disk 14 is a cylindrical, preferably tapered, opening or chamber 18 to receive the rotary valve 19 which is provided with a stem 20 having at its outer end a handle 21. On the end opposite that from which the stem 20 projects, the valve is provided with a short stem 22 having an abutment at its outer end between which and the valve casing is a spring 23 for holding the valve snugly in place in its seat. Through the disk 14 are formed openings 25 and 26 communicating respectively with the openings 9 and 10 of the base 4, and on its front below the disk 14 the valve carrier is provided with a spout 27 communicating with the valve chamber 18.

The valve 19 is provided with a single port or opening 28 of such extent that when the valve is in the position shown in Fig. 1 it will connect openings 25 and 26 and thus permit liquid to flow from the container 1 to the measuring chamber 3, and when turned to its other position will connect the opening 26 with the opening in spout 27.

In the measuring chamber which is preferably cylindrical, is a piston 30 having a hollow stem 31 extending upward through a suitable opening in the cover 32 of the measuring chamber. At its upper end the stem is provided with an outwardly opening valve 33 having a stem 34 extending upward and provided with a cap 35 movable on the stem and provided with spring 36 by which the cap is kept normally raised to keep valve 33 in open position. The valve stem 31 is preferably suitably marked to show the position of the piston and consequently the capacity of the measuring chamber.

The measuring chamber and container are so constructed that the lower face of the piston 30 when at the upper limit of its movement is substantially on a level with the mouth of the inverted bottle 2 so that when the liquid flowing from the container

into the measuring chamber reaches the piston it will at the same time be at the level of the bottle mouth and thus cut off the flow by preventing the admission of air 5 to the bottle. By pressing down on the cap 35 the escape of air from the measuring chamber may be stopped with the effect of stopping the inflow of liquid from the container. The piston may be moved to any 10 desired position in the measuring chamber to determine the amount of liquid to be drawn at a time.

In Fig. 4 we have shown a modified form of the piston for the measuring chamber. 15 In the construction here shown the piston is provided below the end of the hollow stem 31 with a chamber 36 from which a passage 37 leads directly downward and two passages 38 and 39 lead outward and 20 downward to near the periphery of the lower end of the piston. The purpose of this construction is to prevent liquid from being forced upward in the hollow stem by air escaping from the measuring chamber. 25 It sometimes happens with the construction shown in Fig. 1 that a small quantity of liquid gets into the lower end of the hollow stem and remains there and on subsequent operation, and particularly if the piston is 30 moved downward in changing the capacity of the measuring chamber, the air escaping from the measuring chamber forces this liquid up through the stem to spurt out at the top.

35 In the construction shown in Fig. 4 the chamber 36 receives any liquid which would otherwise get into the hollow tube and can drain out freely and should any liquid remain in the chamber the air escaping from 40 the measuring chamber in subsequent operation or as the piston is pushed downward, enters the side passages 38 and 39, as well as the vertical passage 37, and tends to blow across the liquid, if any, in chamber 36 and 45 does not tend to carry it up the hollow stem. These passages 37, 38 and 39 are straight passages readily cleansed.

In Fig. 5 we have shown a construction for the top of a measuring chamber of fixed 50 capacity. In this construction the top 32 is provided with a simple cap 40 having a side opening 41 for escape of air.

The upper portion of the device may be 55 readily lifted from the ring 6 and the parts thus separated for shipment or for other purposes. When the upper portion is thus removed from the base, the valve carrier may be readily removed and the parts cleansed if desired.

60 The legs 7 are adapted to rest on a counter or shelf and in use the bottle of grape juice or other liquid to be dispensed is opened and inverted in the container 2, and at once liquid flows from it until the level of the 65 liquid reaches and seals the bottle mouth.

By turning the valve 19 to the position shown in Fig. 1 the liquid will flow from the container into the measuring chamber until it fills it up to the piston 30. By then turning the valve to its other position the 70 liquid will flow from the measuring chamber through spout 27 into a glass or other receptacle.

Having thus described our invention what 75 we claim is:

1. In a liquid dispensing device, a container adapted to receive and support an inverted bottle, a vertically arranged measuring chamber connected therewith, a common base for the container and measuring chamber, and means carried by the base for controlling the flow of liquid from the container to the measuring chamber.

2. In a liquid dispensing device, a container adapted to receive and support an inverted bottle, a vertically arranged measuring chamber connected therewith, a common base for the container and measuring chamber, means carried by the base for controlling the flow of liquid from the container to 85 the measuring chamber and a piston in the measuring chamber movable therein to regulate its capacity.

3. In a liquid dispensing device, a container adapted to receive and support an inverted bottle, a vertically arranged measuring chamber connected therewith, a common base for the container and measuring chamber, means carried by the base for controlling the flow of liquid from the container to 95 the measuring chamber, and a piston in the measuring chamber movable therein to regulate its capacity having a hollow upwardly extending stem.

4. In a liquid dispensing device, a container adapted to receive and support an inverted bottle, a vertically arranged measuring chamber connected therewith, means carried by the base for controlling the flow of liquid from the container to the measuring chamber, and a piston in the measuring chamber movable therein to regulate its capacity having a hollow upwardly extending stem provided at its upper end with an outwardly opening valve.

5. In a liquid dispensing device, a container adapted to receive and support an inverted bottle, a vertically arranged measuring chamber connected therewith, a common base for the container and measuring chamber, means carried by the base for controlling the flow of liquid from the container to the measuring chamber, and a piston in the measuring chamber movable therein to regulate its capacity having a hollow upwardly extending stem provided at its upper end with an outwardly opening valve, and means for closing the valve.

6. In a liquid dispensing device, a container adapted to receive and support an in- 130

verted bottle, a vertically arranged measuring chamber connected therewith, a common base for the container and measuring chamber, having its lower face flat, a valve carrier having its upper face adapted to fit the lower face of the base, and means for detachably securing the valve carrier to the base.

7. In a liquid dispensing device, a container adapted to receive and support an inverted bottle, a vertically arranged measuring chamber connected therewith, a common base for the container and measuring chamber, having its lower face flat, a valve carrier having its upper face adapted to fit the lower face of the base, means for detachably securing the valve carrier to the base, the base being provided in its lower face with an annular recess, and supporting means comprising a ring adapted to fit said recess and legs carried by the ring.

8. In a measuring device, a chamber hav-

ing an opening for entrance of liquid from below, and a piston movable in said chamber having an upwardly extending hollow stem, the piston having a central vertical passage leading to the lower end of the hollow stem and inclined passages leading from near the periphery of the lower face of the piston to near the lower end of the hollow stem.

9. In a measuring device, a chamber having an opening for entrance of liquid from below, and a piston movable in said chamber having an upwardly extending hollow stem, the piston being provided below the lower end of the stem with a chamber and inclined passages leading to said chamber from near the periphery of the lower face of the piston.

In testimony whereof, we affix our signatures this second day of May, 1919.

HENRY G. CORDLEY.
GEORGE R. LONG.
